UNITED STATES PATENT OFFICE.

ALLEN W. HOLMES AND HIRAM C. HOLMES, OF MIDDLETOWN, CONNECTICUT, ASSIGNORS TO WILCOX, CRITTENDEN AND COMPANY, OF MIDDLETOWN, CONNECTICUT, A COPARTNERSHIP.

DESIGN FOR A STEERING-WHEEL.

SPECIFICATION forming part of Design No. 36,958, dated June 7, 1904.

Application filed April 27, 1904. Serial No. 205,246. Term of patent 7 years.

To all whom it may concern:

Be it known that we, ALLEN W. HOLMES and HIRAM C. HOLMES, citizens of the United States, residing at Middletown, in the county of Middlesex and State of Connecticut, have invented a new, original, and ornamental Design for Steering-Wheels, of which the following is a specification, reference being had therein to the accompanying drawing, forming part thereof, in which the figure repre-

sents in elevation a steering-wheel embodying our design.

What we claim as our invention is—

The ornamental design for a steering-wheel, as shown.
